(57) **CLAIM**

The ornamental design for a bone plate system extender plate, as shown and described.

DESCRIPTION

FIG. 1 is a perspective view of a bone plate system extender plate emphasizing a top surface.

FIG. 2 is a perspective view of a bone plate system extender plate emphasizing a bottom surface.

FIG. 3 is a top view of a bone plate system extender plate.

FIG. 4 is a left end view of an extender plate.

FIG. 5 is a right end view of an extender plate.

FIG. 6 is a right side view of a bone plate system extender plate.

FIG. 7 is a left side view of a bone plate system extender plate.

FIG. 8 is a bottom view of a bone plate system extender plate; and,

FIG. 9 is an alternate embodiment of a perspective view of a bone plate system extender plate emphasizing a top surface.

UNITED STATES PATENT AND TRADEMARK OFFICE
CERTIFICATE OF CORRECTION

PATENT NO. : Des. 505,205 S
DATED : February 1, 2002
INVENTOR(S) : Jim Freid

Page 1 of 1

It is certified that error appears in the above-identified patent and that said Letters Patent is hereby corrected as shown below:

Title page.

Item [54], Title, replace “**BONE PLATE SYSTEM EXTENDER PLATE**” with
-- **EXTENSION PLATE** --.

Item [57], **DESCRIPTION**,

Lines 12-13, delete “FIG. 8 is bottom view of a bone plate system extender plate; and,”
with -- FIG. 8 is bottom view of a bone plate system extender plate. --.

Signed and Sealed this

Twenty-first Day of March, 2006
